PERCY FURLONG HEYES, OF TORONTO, ONTARIO, CANADA, ASSIGNOR TO SIDNEY TORRANCE HEYES, OF TORONTO, ONTARIO, CANADA

PAPER-UTENSIL-FORMING DIE

Application filed July 12, 1928. Serial No. 292,081.

This invention relates to improvements in paper utensil molding dies, as described in the present specification and illustrated in the accompanying drawings which form part 5 of the same.

The invention consists essentially of the novel features pointed out broadly and specifically in the claim for novelty following a description containing an explanation in 10 detail of an acceptable form of the invention.

The objects of the invention are to construct an improved form of paper molding die in which the article is stamped, formed 15 and finished in the one operation; to ensure a clean cut edge on the finished product, thereby reducing the number of culls; to prevent distortion in the article when it is being formed or sheared from the paper stock; to 20 reduce the labor upkeep costs; to simplify the mechanism required and reduce the power consumption; and generally, to provide a paper utensil molding die, simple in operation and capable of accomplishing the afore- 25 said purposes.

In the drawings, Figure 1 is a rear elevational view of the invention.

Figure 2 is an enlarged front elevational view with parts in section to disclose the different working parts.

Figure 3 is a section view taken on line 3—3 in Figure 1.

Figure 4 is a section view taken on line 4—4 in Figure 3.

Like numerals of reference indicate corresponding parts in the various figures.

Referring to the drawings, 10 represents the invention complete, consisting of the male die 11 reciprocally mounted in the male die holder 12, and the female die 13 reciprocally mounted in the female die holder 14, having the flange 15 formed at its base secured to the base plate 16 of the usual press in which these dies are mounted. 17 is a shaft formed 40 on the male die holder 12 and secured to the plunger of the press and actuating the member 12. Lugs or extended portions 18 formed on the side of the member 12 have vertical openings 19 therethrough. Pins 20 secured to the flange 15 extend upwardly

therefrom and enter the opening 19 and form a snug fit therewith when the member 12 is lowered by the cam or crank mechanism of the press, and serve as means for guiding the die 11 into its proper position with the die 13 when forming the utensil.

The male die 11 is formed with the parallel sides 23 and fits snugly into the recessed portion 24 of the member 12 and is reciprocally mounted therein. The upper side of the member 12 is enclosed by the web 25. At regular intervals in the web 25 are countersunk openings 26, and a bolt 27 is reciprocally mounted in the central opening 28 in the countersunk portion 26. The bolt head 27A rests on the shoulder 29 of the countersunk portion. The bolt 27 is threaded into the male die 11 as at 30. Compression springs 31 encircling the bolts 27 impinge against the upper face 32 of the die 11 and against the under face of the web 25 and tend to retain the die 11 in spaced relation therefrom. An electric heating element 34 is placed in the recessed portion 35 in the male die 11 and properly insulated therefrom and has the 70 properly insulated leads 36 and 36A leading out through the web 25 to the source of electrical energy.

A plate 38 secured to the male die 11 by the screws 39 protects the heating element 34 and retains it in place. A flat circular ejector plate 40 is centrally located in the under face of the die 11 and recedes into the recessed portion 41 of the die 11 when the forming action takes place. A plunger 42 is secured to the inner face of the ejector plate 40 and extends upwardly through the centrally located opening 43 in the die 11 and is reciprocally mounted therein. An adjusting nut 45 and a lock nut 46 are threaded on said plunger. A reduced portion 42A of the plunger extends upwardly and is reciprocally mounted in the opening 48 in the web 25. A compression spring 49 impinges against the nut 46 and against the under face of the web 25 and 95 serves to actuate the ejector plate 40.

The female die 13 is formed with the parallel side walls 51 which form a snug fit with the inner walls 52A of the recessed portion 52 formed in the member 14, and is reciprocally 100

mounted therein. A heating element 34A is mounted in the groove 35A formed in the under face of the female die 13 and is properly insulated therein and has the leads 36B and 36C properly insulated and let out through an opening formed in the end wall or web 53 in the member 14 and to the source of electric energy. A plate 38A secured to the under face of the die 13 by the bolts 39A serves to protect and to retain the heating element 34A in place. A shaft 60 extends downwardly through a central opening 62 formed through the plate 61 and forms a snug fit in said opening and is reciprocally mounted therein. An adjusting nut 63 having a lock nut 64 is threaded onto the shaft 60 and supports a washer 65A mounted on said shaft.

A strong compression spring 65 impinging against the under face of the plate 61 and 20 against the washer 65A serves to resiliently retain said plate 61 against the under face of the web 53 and to retain the female die 13 substantially in the position shown in Figures 1 and 2, and to resist the downward 25 pressure of the male die thereon and to compress the springs 31 until the paper utensil is formed. The pressure of the springs 31 on the male die 11 is then great enough to overcome the pressure of the spring 65 and the 30 male die forces the female die to recede into the recess 52. The walls 23 of the male die conform with and form a snug fit with the side walls of the recess 52 and may reciprocate therewith.

35 Bolts 67 are threaded upwardly into the die 13 and carrying cylindrical spacers 68, pass through openings 69 in the plate 61 and have the nuts 70 threaded onto the lower portion thereof. The spacers 68 are reciprocally 40 mounted through openings 71 in the web 53 and serve to retain the die 13 in spaced relation with the plate 61. An ejector plate 40A is centrally mounted in the upper face of the die 13 and is adapted to recede into the recess 41A when the paper utensils are being 45 formed. A plunger 42B is secured to the underside of the plate 40A and extends downwardly through the centrally located opening 43A and is reciprocally mounted therein. Lock nuts and adjusting nuts 45A and 46A, 50 respectively, are threaded onto the plunger 42B. The reduced portion 42C of the plunger 42B extends downwardly and into a centrally located opening 48A in the web 53 and 55 the shaft 60 and is reciprocally mounted therein. A compression spring 49A impinging against the upper face of the web 53 and against the nut 46A, serves to actuate the ejector 40A.

60 The upper and inner corner 75 of the side walls of the member 14 are sharpened and form a shearing edge. The lower edge 76 of the side walls 23 of the die 11 is sharpened and forms a shearing edge which slides past 65 the edge 75 as the male die 11 is forced down

into the recess 52 in the member 14. Thus we see that the edge 76 and the edge 75 form co-acting shearing members and serve to shear the stamped paper utensil from the paper stock. In order to ensure perfect vertical shear, a portion 77 on the under face of the die 11 and adjacent the edge 76 is formed at right angles to the sides 23 and extends inwardly a slight distance. A similarly flattened portion 78 is formed on the upper face of the female die 13 and adjacent the outer periphery of said die 13.

In order to remove the finished utensil from the dies, a dog 90 is pivotally mounted on the side of the member 12 as at 91, and is adapted to slide past a trigger 92 on the downward stroke and to depress said trigger 92 on the upward stroke, thus opening the valve at 92A to allow a blast of air to be forced through the hose 93 and the nozzle 94. 95 A hose 95 leads to any compressed air storage tank and connects through the valve 92A actuated by the trigger 92 to the hose 95. 96 is a platform supporting the paper stock 97 being led into contact with the dies.

In the drawings, an electric heating element is shown mounted in the male die 11 and in the female die 13, but it is to be understood that any of the known heating means, such as steam or gas, may be successfully used 95 to heat the dies without departing from the scope of this invention.

In the operation of this invention, the dies with their supports or holders are mounted 100 on a suitable press, and the female die holder 14 is preferably secured to the base plate, as mentioned above, while the male die holder 12 is secured to the reciprocating part of the press which is actuated by the cam or crank mechanism. The paper stock 97 is fed between the dies 11 and 13 from any convenient direction, and the amount fed in is controlled by the usual feeding mechanism, well known to the art. On the downward stroke of the male die, the ejectors 40 and 40A on coming 105 in contact with the paper stock are forced into their respective recesses 41 and 41A and the paper stock is formed to conform with the surfaces of the die. At the same time, the stock is heated by the dies and considerable 110 pressure is exerted by said dies so that the utensil will retain its form after removal from the die. The compression spring 65 retains the female die in the position shown in 115 Figures 1 and 2 until the paper utensil is formed. The pressure exerted by the springs 31 on the male die 11 then overcomes the pressure of the spring 65 exerted on the female die 13 and forces said female die along with 120 the paper utensil, downwardly into the recess 52. The shearing edge 76 carried on the outer periphery of the male die 11 then contacts with the shearing edge 75 carried on the inner edge of the female die holder 14 and 125 shears the utensil from the paper stock. The

male die 11 is forced downwardly a slight distance into the recess 52. The upward stroke now commences, and when the male die reaches the position adjacent its extremity of upper travel, the ejectors 40 and 40A force the utensil out of contact with the dies 11 and 13, respectively, and the dog 90 actuates the trigger 92 to depress the valve in the hose 95 to allow a blast of air to be forced from the nozzle 94 and blow the utensil away from the dies, substantially in a direction at right angles to the direction of travel of the paper stock.

What I claim is:

15 In paper utensil forming dies, male and female dies having cooperating shearing edges and spring pressed and spring cushioned respectively, ejecting members operating on the release of pressure on said springs and a valve controlled tubular passage and nozzle having an operating trigger and connected to a compressed air supply and directed to the ejected pressed article at an angle to the line of travel of the fed in material.

Signed at the city of Toronto, this 30th day of April, 1928.

PERCY FURLONG HEYES.
